CLAIM

The ornamental design for a soft kettlebell as shown and described.

DESCRIPTION

FIG. 1 is a front, right perspective view of the soft kettlebell;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the drawings depict portions of the soft kettlebell that form no part of the claimed design.
